(57) **CLAIM**

The ornamental design for a keyboard, as shown and described.

DESCRIPTION

1. Keyboard

1.1 is a front, top, and right side perspective view of a keyboard;

1.2 is a rear, top, and left side perspective view thereof;

1.3 is a front elevational view thereof;

1.4 is a rear elevational view thereof;

1.5 is a top plan view thereof;

1.6 is a left side elevational view thereof;

1.7 is a rear, top, and left side perspective view thereof, shown in a folded position;

1.8 is a bottom plan view thereof;

1.9 is a right side elevational view thereof;

1.10 is a front, top, and right side perspective view thereof, shown in a folded position;

1.11 is another front, top, and right side perspective view of a keyboard;

1.12 is another rear, top, and left side perspective view thereof;

1.13 is another front, top, and right side perspective view thereof, shown in a folded position; and,

1.14 is another rear, top, and left side perspective view thereof, shown in a folded position.

(Continued)

The broken lines showing of a keyboard are for the purpose of illustrating environmental structure and form no part of the claimed design.

1 Claim, 14 Drawing Sheets
